FLUID PRESSURE PRODUCING DEVICE

Erwin F. Loweweke, Detroit, Mich., assignor to Hydraulic Brake Company, Detroit, Mich., a corporation of California

Application February 17, 1941, Serial No. 379,360

7 Claims. (Cl. 60—54.6)

This invention relates to fluid pressure producing devices, and more particularly to improvements in the construction and assembly of parts thereof.

A primary object of the invention is to provide a new and improved form of compound cylinder of light and compact design and short length adapted to be manufactured in quantities and at a reasonable cost.

Another object of the invention is the provision of a fluid pressure producing device having low and high pressure chambers formed largely of tubing.

Another object of the invention is to provide a fluid pressure device including a compound cylinder formed of sheet metal tubing, die castings, and stampings.

Another object of the invention is the provision of a fluid pressure producing device including a compound cylinder comprising two concentric sheet metal tubes arranged one within and spaced from the other. One pressure chamber is provided within the inner tube and a second pressure chamber is provided between the two tubes. The two tubes are closed with a common end piece or head having concentric flanges which seat the tubes.

Another object of the invention is the provision of a fluid pressure producing device including a cylinder having a piston reciprocable therein and having a flexible boot secured at one end to the piston and at the opposite end to the cylinder, closing such end of the cylinder and forming a fluid chamber therein between the boot and the piston. The construction is such that the chamber formed between the boot and the piston communicates with the chamber within the opposite end of the cylinder, and as here shown through the piston. The boot chamber also communicates, through an annular chamber formed within the piston contiguous the cylinder, with a fluid reservoir.

Another object of the invention is the provision of a compound cylinder having a large piston and small piston with the pistons arranged in such a manner within the cylinder that the heads of the two pistons lie substantially in the same transverse plane within the cylinder.

A further object of the invention is the provision of a compound cylinder having its low pressure cylinder and its high pressure cylinder arranged one within the other and whereby the chamber of the low pressure cylinder surrounds the cylinder which forms the high pressure chamber.

A feature of the construction is that the low pressure piston which operates within the space between the two cylinders is hollow or annular in shape and the high pressure cylinder telescopes therewith during the compression stroke and the high pressure piston is disposed interiorly of the low pressure piston.

Other objects and advantages of the invention will appear from the following description taken in connection with the drawing forming a part of the specification, and in which—

Fig. 1 is a vertical sectional view of the fluid pressure producing device;

Fig. 2 is a sectional view substantially on line 2—2 of Fig. 1; and

Fig. 3 is a sectional view substantially on line 3—3, Fig. 1.

Referring to the drawing for more specific details of the invention, represented generally at 10 is a cylinder comprising an assembly of tubings, die castings, and stampings which are welded or otherwise suitably secured together to form an integral unit. The cylinder assembly 10 includes a small cylinder 12 and a large cylinder 14, each closed at one end by a common head 16, defining therein respective chambers 18 and 20. The cylinders are open at their opposite ends. Head 16 is provided with concentrically disposed axial flanges 22 and 24 for firmly securing the cylinders 12 and 14 thereto. The head 16 has a discharge port 26 interiorly threaded to receive an outlet pipe, not shown, and is further provided with a circumferential flange 28 for suitably fastening the cylinder assembly 10 to the chassis of an automotive vehicle. These cylinders are thin-walled and of light weight, as would be the case if formed of sheet metal tubes, and hereinafter where the word "tubular" is used to describe the cylinders, such characterization is intended.

Affixed to the cylinder 10 is a suitable connection 30, normally connected to a conventional fluid tank, not shown. Connection 30 has therethrough a port 32 communicating with the chamber 20 by way of passages 34 and 36.

Fitted on the open end of cylinder 12 is a sleeve 38 having an annular shoulder 40 abutting the end of the cylinder. An annular groove 42 in the cylinder 12 communicates with the chamber 20 by way of ports 44 in the sleeve 38 and with the chamber 18 by way of a line passage 46 formed by the shoulder 40 of the sleeve and the end of the cylinder 12. The passage 46 is obtained by the irregularity inherent in rough machining of the abutting end of the sleeve. The sleeve has 55 an extension 48 provided with a bore 50 con-

centric to and of equal diameter with the chamber 18.

A piston 52 is fitted for reciprocation within the cylinder 12, and a piston 54 is reciprocable within the cylinder 14.

As shown, the large piston 54 has a flange 56, and is held against displacement by a washer 58 supported by a retaining ring 60 fitted on the open end of the cylinder 14. The piston has a head 62, a reduced body portion 64, and an internal portion 66. An annular chamber 68 is formed between the cylinder wall and the reduced body portion 64, the flange 56, and head 62 of the piston. This chamber 68 communicates through port 34 and passageway 32 with the fluid chamber of a tank, not shown.

A plug 70 provides in conjunction with the internal portion 66 of the piston a chamber 72. Ports 74 in the portion 66 provide communication between the chamber 12 and a chamber 76 rearward of the flange 56 on the piston 54. This chamber 76 is completed by a boot 86. A groove 80 in the plug 70 cooperates with a groove 82 in the internal portion 66 of the piston so as to securely hold a rib 84 of the flexible boot 86 to secure one end of the boot to the piston. The other end of the boot is ribbed and provided with openings therethrough so as to fasten the boot to the retaining ring 60 by means of bolts 88. The chamber 76 formed by the boot 86 and piston flange 56 communicates with the annular chamber 68 by way of a plurality of ports 90 in the flange 56. The chamber 72 communicates through a ball check controlled bore 78 with the interior of piston 54 and the low pressure chamber.

Plug 70 has a recess formed in its back for the reception of a round-headed pin 92 fitted in the end of a tubular thrust rod 94. A forward end 96 of the plug centers in the chamber 72.

The head 62 of the large piston 54 has a plurality of ports or passages 98 providing communication between the annular chamber 68 and that portion of the large chamber 18 forward of the head 62, and a sealing cup 100 is seated on the head for control of the passages. A spring 102 is interposed between the sealing cup and head 16 of the cylinder 10 and serves to retain the sealing cup against displacement and to return the piston to its retracted position.

The small cylinder 12 with its end sleeve 38 which forms the high pressure chamber extends into the hollowed-out large piston 54 spaced therefrom whereby the large piston telescopes during reciprocation over the cylinder 12. The internal portion 66 of the large piston 54 has an external diameter less than the inside diameter of cylinder 12 to enter therein.

The small piston 52 reciprocable in the chamber 18 has a head 104 provided with a plurality of passages 105 therethrough providing communications between the chamber 18 within the cylinder 12 and the chamber 20 within the cylinder 14 outside of the cylinder 12. A sealing cup 106 on the piston head 104 controls the passages 105 and is held against displacement by a spring 108 interposed between the sealing cup 106 and the head 16 of the cylinder 10. This spring also serves to return the piston to its retracted position. This head has a rearward extension 110 provided with a concentric bore 112, and an end 114 which abuts the internal portion 66 of the piston 54. Gland passages 116 through the end portion 114 establish communication between the bore 112 and the chamber 20. Such passage-

ways 116 also establish communication between chamber 20 and the chamber 72 through the bore 78.

Within the chamber 72 is a ball valve 118 normally held by a spring 120 to close the bore 78. A plunger 122 reciprocable in the bore 110 has a head 124 abutting the sealing cup 106 and an extension 126 extending through the bore 78 and bearing against the ball valve 118.

In a normal operation of the fluid pressure producing device, upon actuation of a suitable mechanism, not shown, force is transmitted therefrom through the thrust pin 94 and pin 92, resulting in forward movement of the pistons 52 and 54 on their compression strokes.

During the initial movement of the pistons 52 and 54 on the compression stroke, the sealing cup 106 on the large piston 54 closes the port 36 through cylinder wall 14 and the sealing cup 20 106 on the small piston 52 closes the line passage 46 between chambers 18 and 20. Thereafter, as the pistons advance, fluid in the chamber 20 is displaced therefrom through the passages 105 in the piston 52, past the sealing cup 106 into the chamber 18, thence through the discharge port 26 into fluid pressure delivery pipes, not shown, for delivery to a suitable mechanism, not shown, requiring fluid pressure.

As the pistons are further advanced, as pressure needs require, the ball valve 118 loaded to a predetermined pressure cracks, due to the fluid pressure on the sealing cup 106 being transmitted through the head 126 of the plunger 122 and its extension 126, thereby unseating the ball. The fluid pressure in the large chamber 20 of the cylinder is thereby relieved and a portion of the fluid is returned from the large chamber 20 through the chamber 72 through the passages 74, the chamber 76, passages 90, annular chamber 68, port 34 and the port 30 into a conventional reservoir or tank, not shown.

Upon release of the applied force, suitable spring means undisclosed return the thrust rod to its retracted position allowing the pistons 52 and 54 to return to their retracted positions under the influence of springs 102 and 108. During this operation, the spring 120 moves the valve 118 to its closed position and piston 54 uncovers port 36 establishing fluid communication between chamber 20 and the fluid reservoir, not shown. Piston 52 uncovers the line passage 46 establishing fluid communication between chamber 18 and chamber 20.

As the pistons 52 and 54 return to their retracted positions, a partial vacuum is created in the chamber 18, and this results in drawing fluid from the reservoir or tank through the port 34, into the annular chamber 68, thence through the passages 98 in the head of the piston 54, past the sealing cup 106 thereon into the chamber 20, thence through the passages 105 in the piston 52, and past the sealing cup 106 thereon into the chamber 18, completely filling the chambers 18 and 20.

With the return of the fluid from the mechanism requiring fluid pressure, the chamber 18 may be in receipt of a quantity of fluid in excess of its capacity, and under this condition the excessive quantity of fluid is displaced therefrom through the line passage 46, the annular groove 42, ports 44, into the chamber 20, thence through the port 36 and the port 20, into the reservoir.

While this invention has been described in connection with certain specific embodiments, the principle involved is susceptible of numerous

other applications that will readily occur to persons skilled in the art. The invention is, therefore, to be limited only as indicated by the scope of the appended claims.

I claim:

1. In the construction of a compound cylinder, a pair of tubular spaced concentric cylinders closed at one end by a head common to both cylinders and open at their other end, pistons reciprocable in their respective cylinders, and 10 a sleeve fitted on the inner cylinder including a part extended beyond the cylinder of equal diameter to the interior of the cylinder adapted to support the piston reciprocable in the inner cylinder and providing in conjunction with the inner cylinder a communication between the cylinders when the piston is in retracted position.

2. In the construction of a compound cylinder, a pair of tubular spaced concentric cylinders, a head common to the two cylinders having axially disposed concentric flanges engaging the cylinders therewith the inner cylinder having an annular groove at its open end, and a sleeve including a part embracing the inner cylinder having ports therethrough communicating with the annular groove and a part coextensive with the cylinder spaced from the open end thereof to provide communication between the cylinders by way of the groove and ports.

3. In the construction of a compound cylinder, a pair of tubular spaced concentric cylinders secured at their one end in a vertical plane to a common end plate on axially disposed concentric flanges forming part of the end plate, pistons reciprocable in the respective cylinders the cylinder of the larger diameter being substantially longer than the cylinder of lesser diameter and braced at its other end by a circumferential ring, and the smaller cylinder embraced by a sleeve 35 fitted on its other end and providing a continuation thereof having the same internal diameter, said sleeve adapted to support the piston reciprocable therein when in its retracted position.

4. In the construction of a compound cylinder, a pair of cylinders of unlike diameters, a head for the cylinders having concentric axially extended flanges thereon, a port through the head concentric the flanges, means on the head 40 for stationary attachment of the cylinder, pis-

tons reciprocable in the respective cylinders, and a sleeve fitted on the smaller cylinder providing in conjunction therewith a communication between the cylinders when the pistons are in retracted position.

5. In a fluid pressure producing device comprising spaced concentric cylinders closed at one end by a common head secured thereon defining a large chamber and a small chamber, pistons reciprocable in the respective chambers, and a sleeve having a part embracing the open end of the small cylinder providing in conjunction with the small cylinder a communication between the chambers.

6. In a fluid pressure producing device, a cylinder closed at one end by a head, piston mechanism reciprocable within the cylinder defining a compression chamber therein between the piston and the cylinder head and having an annular chamber adjacent the cylinder wall, a flexible boot extending between the piston mechanism and the adjacent end of the cylinder defining a fluid chamber at such end of the cylinder between the boot and the piston, said piston having a passageway adjacent the end of the boot connected to the piston mechanism establishing fluid communication between said fluid chamber and said compression chamber, passages through the piston adjacent the end of the boot connected to the cylinder providing communication between the fluid chamber and annular chamber, and a fluid intake into the cylinder communicating with the compression chamber at one end of the piston and with the annular chamber at the opposite end of the piston.

7. A device of the class described comprising a cylinder, a piston reciprocable in the cylinder, said piston having an inner portion and an annular chamber adjacent the cylinder wall, a plug secured in the inner portion of the piston and defining a chamber therein, a flexible boot secured at one end of the piston by the plug and secured at the other end to the cylinder establishing a chamber between the piston and boot, passages in the piston providing communication between the boot chamber and the annular chamber, and ports in the piston providing communication between the boot chamber and the chamber within the piston.
